UNITED STATES PATENT OFFICE.

WARD S. BUNKER, OF WAUKESHA, WISCONSIN.

SELF-SOAPING SHAVING-BRUSH.

1,264,007.

Specification of Letters Patent. Patented Apr. 23, 1918.

Application filed January 7, 1918. Serial No. 210,684.

To all whom it may concern:

Be it known that I, WARD S. BUNKER, a citizen of the United States, and resident of Waukesha, Waukesha county, Wisconsin, 5 have invented new and useful Improvements in Self-Soaping Shaving-Brushes, of which the following is a description, reference being had to the accompanying drawings, which are a part of this specification.

10 This invention has for its object to provide a shaving brush which will carry its own supply of soap or shaving powder and will be capable of discharging a measured quantity thereof into the body of the brush 15 head where it will quickly produce a shaving lather when the brush is applied in the ordinary manner.

Another object of the invention is to provide such a brush with means for thoroughly 20 protecting the powdered lather producing material from the action of water in the ordinary use of the brush.

With the above and other objects in view 25 the invention consists in the self-soaping shaving brush as herein claimed and all equivalents.

Referring to the accompanying drawings in which like characters of reference indicate the same parts in different views:

30 Figure 1 is a central sectional view of a shaving brush constructed in accordance with this invention, the plunger being in its inner position ready for use; and,

Fig. 2 is a similar view thereof with the 35 plunger in its outer position for admitting a charge of lather producing material to the feed barrel.

In these drawings 10 indicates the brush 40 head which as here shown is bound within a sheet metal brush binding 11 having a central tubular feed barrel 12 communicating with the interior of a cylindrical storage chamber 13 which is threaded or otherwise secured to the brush binding 11.

45 The brush binding 11 constitutes a closure for one end of the storage chamber 13, though the tubular barrel 12 therethrough permits of a discharge of the contents of the storage chamber into the interior of the brush 50 head 10 in regulated quantities as determined by the operation of a plunger 14. The plunger 14 is mounted to reciprocate within a tubular guide 15 of a removable screw cap 16 which is threaded on and forms 55 a closure for the other end of the storage chamber 13. By means of a knob 17 on the

end of the plunger stem 14 the plunger may be moved from the position shown in Fig. 1 where its enlarged head 18 fits within the feed barrel 12 to the position shown in Fig. 60 2 where the plunger head is withdrawn entirely from the feed barrel 12 to permit a flow of the shaving powder from the storage chamber into said feed barrel. The shoulder formed by the head of the plunger 65 engages the end of the tubular guide 15 to limit the outward movements thereof, and the engagement of the knob 17 with the screw cap 16 limits its inward movements.

In operation the storage chamber forms 70 a magazine in which the supply of shaving powder 19 is placed when the screw cap is removed. When it is desired to use the brush, it is dipped in water and then the plunger is withdrawn to admit the powder 75 to the feed barrel and again depressed to force a charge of powder out of the feed barrel and into the brush proper, where it is in best position to be worked up into a lather on the face. The size of the feed 80 barrel is such that there is no waste of shaving powder and only the necessary quantity for a shave is discharged with each operation of the plunger.

The end of the plunger head is preferably 85 made slightly tapering and the end of the feed barrel is preferably slightly flaring to facilitate the entry of the plunger in the feed barrel.

By means of this invention the shaving 90 brush is made to provide a charge of soap or shaving powder within the brush head where it will readily be dissolved and worked into a lather by the movements of the brush. The discharge of the shaving 95 powder into the interior of the brush head causes it to be retained by the brush head until it is completely dissolved and worked up into a lather, instead of being deposited in one place, as frequently happens where 100 the powder is applied to the exterior of the brush head. The spread of the brush fibers effectively seals the end of the barrel so that the powder does not have an unlimited flow when the plunger is raised. The feed 105 barrel is of such a length as to continue through the binding of the brush head where the brush fibers are under compression and conduct the charge of powder to the portion of the brush where the brush 110 fibers have considerable movement and are capable of working it into a lather. This

long barrel and the correspondingly long coöperating plunger head protect the shaving powder in the storage chamber from the water in the brush and even though the 5 brush is allowed to stand in water there is no danger of the powder becoming damp so as to interfere with the free movement when the plunger is withdrawn. The end of the plunger head passes beyond the end 10 of the feed barrel to prevent obstruction of the latter that might otherwise be formed by the powder becoming caked in the end thereof.

The shaving brush of this invention does 15 not materially differ in its appearance from the ordinary shaving brush and its features of advantage are obtained without materially increasing the cost.

I desire it to be understood that this invention is not limited to any specific form 20 or arrangement of parts except in so far as such limitations are specified in the claim.

What I claim as new and desire to secure by Letters Patent is:

25 A shaving brush, comprising a tubular

handle forming a magazine for containing shaving powder, a brush head having a metal binding threaded in one end of the handle and provided with a central tubular feed barrel leading from the magazine to 30 the interior of the brush head, a screw cap threaded on the other end of the handle and having an inwardly extending tubular guide, a plunger having a stem portion fitting within the tubular guide and a plunger 35 head working within the feed barrel and engaging the tubular guide when withdrawn from the feed barrel for limiting its upward movement, said guide being the sole means for directing said plunger, and means 40 on the end of the plunger stem for engaging the screw cap and limiting the downward movement of the plunger.

In testimony whereof, I affix my signature, in presence of two witnesses.

WARD S. BUNKER.
